UNITED STATES PATENT OFFICE.

SADIE W. RAY, OF ANNAPOLIS, MARYLAND.

DESIGN FOR A WATCH-STAND FOR TOILET-TABLES.

SPECIFICATION forming part of Design No. 31,817, dated November 14, 1899.

Application filed October 16, 1899. Serial No. 733,832. Term of patent 3½ years.

To all whom it may concern:

Be it known that I, SADIE W. RAY, a citizen of the United States, residing at Annapolis, in the State of Maryland, have invented a new and original Design for a Watch-Holder for the Toilet-Table, of which the following is a specification.

This invention relates to a new and original design for a watch-holder for the toilet-table, and has for its object to provide a design of this kind that shall be both useful and ornamental.

The leading feature of the design consists of the form of one of the ancient Japanese torii or bird's rests, the top piece being a curved section with flat angle on the upper face which curves upward at the ends, the convex side resting on and fitting to a straight piece of slightly less width and length, as indicated in the drawings. The lower flat edge of the latter piece near the outer ends rests upon two cylindrical uprights or posts, which are set in at a slight angle and secured thereto, so as to give increased width for the frame at the foot. The upright posts are set into a convex torus or circular base, the flat side of which is in diameter slightly smaller than the supporting square pedestal, which is chased or molded to represent a stone foundation, this lowest base or tread being made solid to give weight and stability to sustain the su-

perstructure. A flat horizontal tie-beam pierces the posts a short distance below and parallel to the cross-piece above it and is double-wedged on both inner and outer sides of the posts. The parallel cross-pieces are connected in the middle by a vertical plate; and from below the center of the lowest cross-piece springs outward with upward curve the hook from which the watch is to be held pendant, as indicated in the drawings.

Referring to the drawings, in which Figure 1 is a front view, and Fig. 2 is a side elevation, the letter *a* designates the upper cross-piece; the letter *b*, the next straight piece fitting thereto; the letters *c c*, the cylindrical posts; *d d*, the torii or circular bases; *e e*, the square pedestals; *f*, the lowest cross-tie beam; *g g*, the wedges; *h*, the flat connecting-plate, and *i* the hook upon which the watch is to be hung, completing the design.

What I claim is—

The design for a watch-stand for the toilet-table herein shown and described.

In testimony that I claim the foregoing design as my own I have hereto affixed my signature in the presence of two witnesses.

SADIE W. RAY.
